AUXILIARY MOTORCYCLE SEAT

Paul W. Svehla, 3985 La Crescenta Road, El Sobrante, Calif. 94803, and Samuel R. McQuisten, 933 Oxford St., Berkeley, Calif. 94707

Filed July 15, 1971, Ser. No. 163,130

Term of patent 14 years

Int. Cl. D12—11

U.S. Cl. D90—16

FIG. 1 is a top plan view of an auxiliary motorcycle seat showing our new design;

FIG. 2 is a front elevational view of the auxiliary motorcycle seat;

FIG. 3 is a rear elevational view of the auxiliary motorcycle seat;

FIG. 4 is a left-side elevational view of the auxiliary motorcycle seat;

FIG. 5 is a right-side elevational view of the auxiliary motorcycle seat; and

FIG. 6 is a bottom plan view of the auxiliary motorcycle seat.

We claim:

The ornamental design for an auxiliary motorcycle seat, as shown and described.
